(57) **CLAIM**

The ornamental design for a coring machine, as shown and described herein.

DESCRIPTION

FIG. 1 is a front perspective view of a coring machine showing my design.

FIG. 2 is a front view of the coring machine of FIG. 1.

FIG. 3 is a back view of the coring machine of FIG. 1.

FIG. 4 is a side view of the coring machine of FIG. 1.

FIG. 5 is a side view of the coring machine of FIG. 1.

FIG. 6 is a top view of the coring machine of FIG. 1; and,

FIG. 7 is a bottom view of the coring machine of FIG. 1.

1 Claim, 6 Drawing Sheets**FIG. 1**

FIG. 2

FIG. 3

FIG. 4

FIG. 5

FIG. 6**FIG. 7**
